GARBAGE CAN COVER LOCK

Herman F. Zehnder, Bay City, Mich.

Application August 31, 1951, Serial No. 244,508

2 Claims. (Cl. 292—258)

1

This invention relates to receptacle or can cover holders, and more specifically, has reference to a device for lockably engaging covers such as those used on large garbage, feed and ash cans.

If the covers or lids of receptacles of the type stated are not held down securely, they are subject to easy removal by small children, dogs, or marauding animals. In such instances, the contents of the receptacle are often spilled into the surrounding area, which obviously results in a nuisance and an unsanitary condition in said area.

The present invention, accordingly, has as one important purpose thereof the provision of a means for holding the cover or lid securely upon cans of the type stated, so as to preclude the possibility of removal of said covers or lids except, of course, when it is desired to empty the can or add material to that already contained within the can.

Another important object is to provide a device of the character described which can be manufactured at relatively low cost, and will be capable of application to a wholly conventional can and its associated cover with maximum speed and ease.

Still another important object is to provide a device of the character described which is applicable to any conventional garbage or trash can equipped with side handles, the device being so designed as to act efficiently regardless of variations in size or shape of the can.

Yet another important object is to provide a device of the character stated which is easily, quickly and effectively installed upon a garbage or trash can without requirement of structural additions, changes, or modifications in the can.

Still another important object is to provide a cover lock or holder for trash cans so designed as to exert pressure, when installed upon the can, upon the center portion of the lid and upon diametrically opposite marginal portions of said lid, thus to hold the lid securely upon the body of the trash can.

Other objects will appear from the following description, the claims appended thereto, and from the annexed drawing, in which like reference numerals designate like parts throughout the several views, and wherein:

Figure 1 is a top plan view of a cover holder or lock formed in accordance with the present invention, as it appears when applied to a conventionally designed trash can;

Figure 2 is a side elevational view, a portion of the holder being shown in longitudinal section;

2

Figure 3 is a perspective view of the holder disassociated from the trash can; and

Figure 4 is an enlarged sectional view taken substantially on line 4—4 of Figure 1.

Referring to the drawings in detail, the reference numeral 5 designates the body of a conventionally formed garbage or trash can, said can including the lid 6 having the depending peripheral flange 8 engaging over the upper end 10 of the body 5.

Secured rigidly to the outer surface of the lid, and disposed centrally of the lid, is a handle 10.

In accordance with the present invention I provide an elongated, flat lock bar 12, which may be formed of any suitable material, such as steel, plastic or the like. In the preferred embodiment of the invention, said lock bar is formed of a material capable of being flexed longitudinally, for reasons to be made apparent hereinafter.

Adjacent the opposite ends of the lock bar 12, I form in said bar openings 14, receiving the shanks of elongated eye bolts 16. As seen from Figure 2, the openings 14 are smooth walled, and are of appreciably greater diameter than the diameter of the shanks of the eye bolts, so as to permit a limited amount of free movement of the eye bolt relative to the end of the lock bar associated therewith, which movement may be desirable depending upon the design or formation 30 of the particular trash can to which the device is to be applied.

The elongated, threaded shanks of the eye bolts 16 are threadable through longitudinal bores 18 having internal threads complementary to the threads of the eye bolts, said bores being formed in solid plugs 20, so as to extend longitudinally and centrally of said plugs, and open at opposite ends of the plugs.

In the illustrated example, the plugs are formed with spiral grooves 22, on which may be threaded the upper end of coil springs 24, so as to secure said springs fixedly to the plugs. At their other ends, the springs 24 are engaged with the upper loops of S-hooks 26, which upper loops are closed 45 to prevent accidental separation of the springs from the S-hooks.

A garbage can of the type illustrated in the drawing is conventionally provided with diametrically opposite, outward extending handles 28, spaced from the upper ends of the cans to an extent selected by the particular manufacturer. In some instances, said handles are spaced only a short distance from the upper ends of the cans, while in other instances, the handles are spaced 55 an appreciably greater distance. The present

device, in this connection, is adapted for application to the handles 28 of a garbage can regardless of the distance of the handles from the upper end of the can. I obtain this characteristic in the invention, by threadable adjustment of the eye bolts 16 in the plugs 20. Obviously, by threading the eye bolts downwardly through the plugs, the distance between the S-hooks 26 and the ends of the lock bar 12 disposed thereabove can be varied without affecting the amount of expansion or pull of the springs, said adjustment being operative to permit application of the holder to any of various makes of trash cans.

Should the handles 28 be spaced from the upper end of the can a distance greater than that illustrated in Figure 2, it is necessary merely to thread the eye bolts upwardly out of the plugs 20, to the extent found most desirable.

In assembling the device with the lid of a trash can, the user first extends the lock bar 12 through the handle 10. Thereafter, the user extends the eye bolts 16 through the openings 14, and threads said eye bolts into the plugs 20 associated therewith to that extent found desirable. The S-hooks 26 are then placed in engagement with the handles 28, placing the springs 24 under tension. As a result, the opposite ends of the lock bar 12 are flexed downwardly as illustrated in Figure 2, so that the end portions of said bar are engaged against diametrically opposite marginal portions of the lid 6, the points of contact between the lock bar and said marginal portions being designated 30. As a result, heavy downward pressure is exerted against the lid 6 at the center of the lid, and at diametrically opposite marginal areas thereof. As a result, the lid is securely held upon the body 5 of the trash can, and is incapable of being removed by marauding animals or the like.

At such time as it may be desired to have access to the interior of the trash can, it is merely necessary to unhook one of the S-hooks 26 from the handle 28 associated therewith, this permitting easy removal of the lid or cover 6.

I believe it will be apparent that the cover lock formed in accordance with the present invention can be applied to any of various makes of trash cans, without modification or structural additions to said cans, and without formation of the device itself with special modified features. The adjustable feature at the opposite ends of the device permits use of the device on trash cans in which the spacing of the handles 28 from the upper end of the can may vary. In each instance, the spring 24 is placed under a predetermined tension, to hold the lid securely upon the body of the receptacle or can.

It is believed clear that the invention is not necessarily confined to the specific use or uses thereof described above, since it may be utilized for any purpose to which it may be suited. Nor is the invention to be necessarily limited to the specific construction illustrated and described, since such construction is only intended to be illustrative of the principles of operation and the means presently devised to carry out said

principles, it being considered that the invention comprehends any minor changes in construction that may be permitted within the scope of the appended claims.

What is claimed is:

1. In combination, a can body having an open upper end, diametrically opposite side handles spaced from the upper end of the body, a removable cover on said upper end having a raised center portion and a bail handle centered upon said center portion, an elongated flexible lock bar proportioned to extend substantially diametrically across said cover through the bail handle and having its ends projecting beyond the periphery of the cover; vertically arranged springs extending along opposite sides of the can body between the cover and the respective side handles; and means connecting the upper ends of the springs to the projecting ends of the lock bar for adjustment of said upper ends of the springs toward and away from the lock bar, said means including bolts rotatably mounted upon and depending from the ends of the lock bar and plugs having axial, threaded bores receiving said bolts, for adjustment of the plugs longitudinally of the bolts responsive to rotation of said bolts, said plugs having their outer surfaces spirally grooved for threading of the plugs into the upper ends of the springs, said springs being detachably connected at their lower ends to the said side handles to tension the springs and flex the lock bar into engagement with the center and diametrically opposite marginal areas of the cover, said springs and lock bar coacting to bias the cover in the direction of the body.

2. In combination, a can body having an open upper end, a removable cover on said upper end, diametrically opposed side handles on the exterior of said can body and spaced below the upper end of the can body, a raised center portion on said cover, a bail handle on said center portion, an elongated flexible lock bar, said lock bar being greater in length than the diameter of the cover and can body and having opposed free ends, said lock bar overlying the cover diametrically and extending through said bail handle, and spring means acting between the free ends of the lock bar and said side handles and flexing said lock bar downwardly into engagement with said center portion and other portions of the cover, said lock bar being otherwise unsecured to said cover.

HERMAN F. ZEHNDER.
